CLAIM

The ornamental design for a prosthetic valve and holder, as shown and described.

DESCRIPTION

FIG. 1 is perspective view of a prosthetic valve and holder; FIG. 2 is a front view of the prosthetic valve and holder of FIG. 1;

FIG. 3 is a back view of the prosthetic valve and holder of FIG. 1;

FIG. 4 is a left side view of the prosthetic valve and holder of FIG. 1;

FIG. 5 is a right side view of the prosthetic valve and holder of FIG. 1;

FIG. 6 is a top view of the prosthetic valve and holder of FIG. 1; and,

FIG. 7 is a bottom view of the prosthetic valve and holder of FIG. 1.

The broken lines in the drawings are for illustrative purposes only and form no part of the claimed design.
